UNITED STATES PATENT OFFICE.

JAMES E. GILBERT AND GLENN W. HARRIS, OF CHICAGO, ILLINOIS.

BACK-BAR TRANSFER MECHANISM FOR SMUT-SHEETING MACHINES.

Application filed June 7, 1920. Serial No. 387,257.

To all whom it may concern:

Be it known that we, JAMES E. GILBERT and GLENN W. HARRIS, citizens of the United States, residing at Chicago, county of Cook, 5 and State of Illinois, have invented a certain new and useful Improvement in Back-Bar Transfer Mechanism for Smut-Sheeting Machines, of which the following is a specification.

10 Patent Number 966,739 to J. E. Gilbert, issued August 9, 1910, illustrates and claims a machine for taking care of sheets of printed or lithographed matter between the time they receive the impression of ink and the 15 time they are sufficiently dried to prevent offsetting when placed on a pile. Broadly speaking, that machine includes the use of an intermittently moving and successively folding strip of cloth between which successive sheets of printed paper are placed immediately on being printed, and in which they are carried until sufficiently dried to be automatically delivered from the machine, all as will more fully appear from the 25 inspection of said patent.

The successive portions of cloth between which the paper is held are divided or marked one from another by cross bars 52 which in the operation of the machine slide 30 downward through guides or channels 44 and 45 as fully set forth in said patent and when released from the bottoms of said guides they travel with the cloth back to points above the tops of the respective 35 guides.

As shown in said patent (Figure 3) when the portion of the cloth carrying the bar arrives over the rear vertical guide 46 the cross bar is a considerable distance above the 40 upper end of the vertical guide and mechanism shown in that patent has to be provided for moving the bar down into the guide while the roller 69 is in the position shown in Figure 3 and before it begins to 45 move to the right, as viewed in that figure, as fully set forth in that patent.

The object of this invention is to provide an improved mechanism automatically operated by the machine for traveling up and 50 grasping the bar on the cloth in the position described, moving the bar down and latching it into the vertical guide and then repeating the operation with the next bar that comes to proper position above the guide.

55 The invention consists in mechanism for carrying out this and other objects, which

can be comparatively easily built and installed in the machine, which is more positive in operation than previous devices, therefore more satisfactory in operation, 60 and which is not liable to get out of order. More particularly the invention consists in many features and details of construction hereafter more fully set forth in the specification and claims. 65

Referring to the drawings in which like numerals denote like parts throughout the several views,

Figure 1 is a side elevation of so much of a machine of the type illustrated in said 70 prior patent as appears necessary to make the invention clear.

Figure 2 is a plan view of the essential portion of the machine taken at the right hand half of Figure 1. 75

Figure 3 is an enlarged side view of a mechanism at the upper right hand corner of Figure 1, part of the frame being broken away to show the desired parts in detail.

Figure 4 is a fragmentary plan view of a 80 track appearing in the left hand upper quarter of Figure 2 showing the details of the parts which are broken away in Figure 2.

Figure 5 is a slightly changed position 85 back view of the bar gripping and carrying mechanism shown in the left hand half of Figure 2.

Figure 6 is a very slightly changed position 90 enlarged front view of the same mechanism as shown in the left hand half of Figure 3, the same being a reversed view in slightly changed position of Figure 5.

Figure 7 is a side view of the mechanism of Figure 6 certain parts being shown in 95 section.

Figure 8 is a front view of the gripping mechanism in the extreme upper position which it assumes in going after a crossbar to transfer it into the vertical guides. 100

Figure 9 is a changed position of the essential parts of Figure 8 showing their condition in the lowest position which they assume in delivering a bar to a vertical guide.

Figure 10 is a fragmentary view of the 105 mechanisms of Figures 8 and 9, in the position of Figure 9 showing latches 94 attached to the vertical guides.

Figure 11 is a sectional detail plan view on the line 11—11 of Figure 9. 110

The mechanism of this invention is shown applied to a modern machine of the type set

forth in said prior Gilbert patent, carried on oppositely disposed parallel side frames 16, only one of which appears in Figure 1, in which are located vertical guides 18 and 20, within which the cross bars 22 carried by the cloth 24 slide vertically in the smutting operation, as heretofore referred to, in connection with said prior Gilbert patent. In this machine the cloth is driven by rollers 26—lever mechanism 28—actuated by a cam mechanism 30. A cross bar 22 leaving the bottoms of the rear vertical guides is moved along a track 32 over rollers 34 until it arrives at a point over the tops of the rear vertical guides 20. When the bar reaches this position the machine automatically removes a bridge piece 36 from across a slot 38 so that the bar can be grasped by the mechanism of this invention and carried down into the vertical guides 20.

Much of the mechanism thus far described is more fully shown, described and claimed in our prior application Serial No. 370,261, filed March 21, 1920.

As fully set forth in said prior Gilbert patent and as shown in plan view in Figure 2 the guides 20 (one on each side of the machine, but only one shown) are of U-shaped or channel shaped cross section so that the ends of the bars 22 lying horizontal rest in them and are held against movement in any horizontal direction while they move vertically through the guides downward through the machine. As shown in Figures 1 and 3, each such guide 20 extends upward in the frame of the machine to a point in proximity to but at a distance sufficiently below the upper horizontal section of track 32 and its slot 38, heretofore referred to, so that the rollers 26 can pass backward and forward on track 32 over the guide 20 as required by the law of the main machine.

Enclosing the three solid sides of the guide 20 is a U-shaped cross head 40 having on its lower central portion a stud 42 to which is attached a connecting rod 44 driven by a lever 46—cam mechanism 48—actuated by the power shaft 50 of the machine with the result that the cross head is reciprocated up and down the guide 20 in proper timing to perform the functions described hereafter as they should occur in the complete automatic operation of the machine. This cross head 40 also carries another stud 52 to which is connected a lever mechanism 54 which automatically operates the bridge piece 36, heretofore referred to.

Rigid with opposite sides of the cross head 40, in the particular case here illustrated, made separable and secured thereto by screws 56, are upwardly rising, relatively thin, wing plates 58 separated one from the other by the width of the channel opening in the guide 20 against whose front

flange edges they slide. In other words, these plates 58 overlap the front edges of the cross head sufficiently to engage the front edges of the side flanges of the guide and thus prevent the cross head from slipping off from the guide in the act of reciprocating.

The main function, however, of wing plates 58 is to afford mounting facilities for latch mechanisms which are required in the carrying out of the main objects of this invention. Each wing plate 58 is provided with a pivot pin or stud 60 located near the cross head 40 proper and a guiding pin 62 located near the upper end of the wing plate 58 where the bar gripping function is to be performed. Concentrically mounted upon each pivot pin 60 are two levers, one of them 64 carrying at its upper end what will be for convenience designated the overlapping latch 66, the other lever 68 carrying at its upper end what will be for convenience designated an underlapping latch 70. Both of these levers are entered by the guide pin 62 through elongated slots 72 formed in the levers to allow lateral rocking of the levers transversely of the guide pin.

The lower end of lever 64 is pressed outward from the cross head by a compression spring 74 bearing against a flange 76 on the lever. Similarly the lower end of lever 68 is pressed outward from the cross head by a compression spring 78 bearing against a flange 80 on the lever. The result of this construction is that both levers 64 and 68 and consequently their latches 66 and 70 normally at all times assume the position shown in Figures 5, 6 and 8. Lever 64 always remains in this position except when its upper angularly inclined face 82 is forced against a cross bar 22 on track 32 as the cross head is moving the parts up to the position of Figure 8 in which case just before the mechanism reaches that position, the overlapping latch 66 is automatically sprung backward away from the cross bar 22 and toward the adjacent wing plate 58 sufficiently to allow the overlapping latch 66 to snap over the bar with the result that the two opposite overlapping latches grasp the top of the bar under the action of springs 74 as shown in the figures.

On the other hand the lower end of each lever 68 is provided with a cam stud 84 and roller 86 adapted when the parts approach and reach the position of Figure 9 and the dotted line position of Figure 5 to contact with an adjacent bracket cam 88 rigidly secured on the guide 20 by any suitable means as for instance the screws 90. This cam face 88 is so shaped and located with reference to the travel of the cross head and attached parts that the underlapping latch 70 sustains the cross bar 22 from the time it is grasped, while on the track 32, until it

has been carried down to a proper predetermined position adjacent to the top of the pile of previously deposited cross bars 22 in the guide 20, whereupon the roller 86 engages the cam 88 and causes the underlapping latch 70 to move to the position of Figure 9 where it entirely clears the bar for purposes which will be hereafter made apparent.

10 Projecting from each side flange of the guide 20 is a pivot pin 92 on which is mounted, for lateral rocking movement, a latch dog 94, let into a suitable recess 96, formed in the adjacent edge of the flange of the guide. This dog 94 is spring pressed toward the center of the guide 20 by spring 98. In the particular case here illustrated, this spring is secured to one side of the guide by screws 100 and has its free end engaging 20 a cross lug 102 projecting from the side of latch dog 94. Therefore this cross lug limits the movement of the tooth 104 of the latch dog 94 inside the guide 20. The latch mechanisms 94-104 one on each side of the 25 guide are so located that they will be forced open against the action of springs 98 by a downwardly passing bar 22 and will then spring back over the top of said bar after it has passed the teeth 104 and thus positively 30 retain it in the guides.

As soon as these latch teeth 104 take hold of the freshly deposited bar 22, the underlapping latches 70 which supported the bar in its downward movement to this point cannot begin to move upward while in their latched position without shearing the bar between the two latches. It is therefore necessary in order to return the cross head including the underlapping latches 70 to the 40 position of Figure 8, to bring down a new bar that at the bottom of the stroke these underlapping latches 70 get out of the way of the recently deposited bar now held by teeth 104 and stay out of its way until they 45 have passed above it. This result is accomplished by so shaping the cam mechanism 88 that the levers 68 with their underlapping latches 70 swing to the position of Figure 9 at the moment the downward movement of the mechanism forces the descending cross bar 22 into engagement with the latches 104 and retains the latches 70 in that 50 position while the bar is passing and being grasped by latches 104 and still retains them 55 in that position until on the upper stroke of the cross head the underlapping latch teeth 70 pass this recently deposited bar held by latches 104 whereupon the cams release these levers and their latches so that the 60 springs 78 return these underlapping latches to normal position ready to perform their proper functions as the next succeeding bar is grasped from the track in the manner described.

65 In the complete operation of the device

the machine shown, in that part of its operation which does not enter into this particular invention carries a bar 22 along track 32 and finally deposits it on bridge piece 36 over slot 38. At this time the cam mechanisms connected with shaft 50 start the cross head 40 upward. This causes lever mechanism 54 to withdraw the bridge piece 36 from below the bar as fully set forth in our said prior application, but before this is completed so that the bar can fall through slot 38 the overlapping latches 66 engage the bar on their inclined faces 82 and snap over the sides of the bar into the position shown in Figure 8. Further rotation of shaft 50 now causes cross head 40 to descend—finally reaching the position of Figures 9 and 10 wherein the latch teeth 104 snap over the top of the bar to retain it in the guide so that it can neither turn over sideways nor return up the guide, and the underlapping latches 70 are withdrawn from beneath the bar and held by cams 88 in this position until on the return stroke of the cross head these underlapping latches 70 are safely above the previously deposited bar when they spring back to normal position ready to support the next bar in its descent from the track into the guide.

Having thus described our invention what we claim as new and desire to secure by Letters Patent, is:—

1. In mechanism of the class described, a guide along which a bar may travel, a bar adapted for travel along the guide under its control, a temporary support for the bar at a point remote from the end of the guide, a bar carrier movable between the support and guide bar gripping mechanism on the carrier, means for moving the bar carrier between two positions in one of which it grasps the bar on the temporary support, and in the other of which it leaves the bar under control of the guide, and automatic means operating the bar gripping mechanism on approaching the last mentioned position to disengage it from the bar and permit it to return to the first position without interference by the delivered bar.

2. In mechanism of the class described, a guide along which a bar may travel, a bar adapted for travel along the guide under its control, a temporary support for the bar at a point remote from the end of the guide, a bar carrier movable between the support and guide, bar gripping mechanism on the carrier, means for moving the bar carrier between two positions in one of which it grasps the bar on the temporary support, and in the other of which it leaves the bar under control of the guide, automatic means operating the bar gripping mechanism on approaching the last mentioned position to disengage it from the bar and permit it to return to the first position without inter-

ference by the delivered bar, and latch mechanism in connection with the guide, adapted to automatically engage the delivered bar operative as the carrier gripping mechanism 5 releases the bar to hold it with reference to the guide.

3. In mechanism of the class described, a guide along which a bar may travel, a bar adapted for travel along the guide under its 10 control, a temporary support for the bar at a point remote from the end of the guide, a bar carrier reciprocatable along the guide toward the support, bar gripping mechanism on the carrier, means for moving the 15 bar carrier between two positions in one of which it grasps the bar on the temporary support and in the other of which it leaves the bar under control of the guide, and automatic means operating the bar gripping mechanism on approaching the last mentioned position to disengage it from the bar and permit it to return to the first position without interference by the delivered bar.

4. In mechanism of the class described, a 25 guide along which a bar may travel, a bar adapted for travel along the guide under its control, a temporary support for the bar at a point remote from the end of the guide, a bar carrier reciprocatable along the guide 30 toward the support, bar gripping mechanism on the carrier, means for moving the bar carrier between two positions in one of which it grasps the bar on the temporary support and in the other of which it leaves 35 the bar under control of the guide, automatic means operating the bar gripping mechanism on approaching the last mentioned position to disengage it from the bar and permit it to return to the first position 40 without interference by the delivered bar, and latch mechanism in connection with the guide, adapted to automatically engage the delivered bar operative as the carrier gripping mechanism releases the bar to hold it 45 with reference to the guide.

5. In mechanism of the class described, a vertical guide down which the end of a bar may travel, a bar adapted to so travel by gravity, a temporary support for the bar 50 above and clear of the guide, a bar carrier, bar gripping mechanism on the carrier, means for moving the bar carrier between two positions in one of which it grasps the bar on the temporary support and in the 55 other of which it leaves the bar under control of the guide, and automatic means operating the bar gripping mechanism on approaching the last mentioned position to disengage it from the bar and permit it to 60 return to the first position without interference by the delivered bar.

6. In mechanism of the class described, a vertical guide down which the end of a bar may travel, a bar adapted to so travel by gravity, a temporary support for the bar 65

above and clear of the guide, a bar carrier, bar gripping mechanism on the carrier, means for moving the bar carrier between two positions in one of which it grasps the bar on the temporary support and in the 70 other of which it leaves the bar under control of the guide, automatic means operating the bar gripping mechanism on approaching the last mentioned position to disengage it from the bar and permit it to 75 return to the first position without interference by the delivered bar, and latch mechanism in connection with the guide, adapted to automatically engage the delivered bar operative as the carrier gripping mechanism releases the bar to hold it with 80 reference to the guide.

7. In mechanism of the class described, a guide along which a bar may travel, a bar adapted for travel along the guide under its 85 control, a temporary support for the bar at a point remote from the end of the guide, a bar carrier movable between the support and guide, spring actuated bar mechanism on the carrier adapted to engage two opposite sides of a bar, means for moving the bar carrier between two positions in one of which it grasps the bar on the temporary support, and in the other of which it leaves the bar under control of the guide, and automatic means operating the bar gripping mechanism on approaching the last mentioned position to disengage it from the bar and permit it to return to the first position without interference by the delivered bar. 100

8. In mechanism of the class described, a guide along which a bar may travel, a bar adapted for travel along the guide under its control, a temporary support for the bar at a point remote from the end of the guide, a bar carrier movable between the support and guide, spring actuated bar gripping mechanism on the carrier adapted to engage two opposite sides of a bar, means for moving the bar carrier between two positions in one of which it grasps the bar on the temporary support, and in the other of which it leaves the bar under control of the guide, automatic means operating the bar gripping mechanism on approaching the last mentioned position to disengage it from the bar and permit it to return to the first position without interference by the delivered bar, and latch mechanism in connection with the guide, adapted to automatically engage the delivered bar operative as the carrier gripping mechanism releases the bar to hold it with reference to the guide. 110

9. In mechanism of the class described, a 125 guide along which a bar may travel, a bar adapted for travel along the guide under its control, a temporary support for the bar at a point remote from the end of the guide, a bar carrier reciprocatable along the guide 130

toward the support, spring actuated bar gripping mechanism on the carrier adapted to engage two opposite sides of a bar, means for moving the bar carrier between two 5 positions in one of which it grasps the bar on the temporary support and in the other of which it leaves the bar under control of the guide, and automatic means operating the bar gripping mechanism on approaching 10 the last mentioned position to disengage it from the bar and permit it to return to the first position without interference by the delivered bar.

10. In mechanism of the class described, a 15 guide along which a bar may travel, a bar adapted for travel along the guide under its control, a temporary support for the bar at a point remote from the end of the guide, a bar carrier reciprocatable along the guide 20 toward the support, spring actuated bar gripping mechanism on the carrier adapted to engage two opposite sides of a bar, means for moving the bar carrier between two positions in one of which it grasps the bar 25 on the temporary support and in the other of which it leaves the bar under control of the guide, automatic means operating the bar gripping mechanism on approaching the last mentioned position to disengage it 30 from the bar and permit it to return to the first position without interference by the delivered bar, and latch mechanism in connection with the guide, adapted to automatically engage the delivered bar operative 35 as the carrier gripping mechanism releases the bar to hold it with reference to the guide.

11. In mechanism of the class described, a vertical guide down which the end of a 40 bar may travel, a bar adapted to so travel by gravity, a temporary support for the bar above and clear of the guide, a bar carrier, spring actuated bar gripping mechanism on the carrier adapted to engage two opposite 45 sides of a bar, means for moving the bar carrier between two positions in one of which it grasps the bar on the temporary support and in the other of which it leaves the bar under control of the guide, and automatic 50 means operating the bar gripping mechanism on approaching the last mentioned position to disengage it from the bar and permit it to return to the first position without interference by the delivered bar.

55. 12. In mechanism of the class described, a vertical guide down which the end of a bar may travel, a bar adapted to so travel by gravity, a temporary support for the bar above and clear of the guide, a bar carrier, 60 spring actuated bar gripping mechanism on the carrier adapted to engage two opposite sides of a bar, means for moving the bar carrier between two positions in one of which it grasps the bar on the temporary support 65 and in the other of which it leaves the bar

under control of the guide, automatic means operating the bar gripping mechanism on approaching the last mentioned position to disengage it from the bar and permit it to return to the first position without interference by the delivered bar, and latch mechanism in connection with the guide, adapted to automatically engage the delivered bar operative 70 as the carrier gripping mechanism releases the bar to hold it with reference to the guide. 75

13. In mechanism of the class described, a stationary guide member for a bar, a cross head moving parallel to the guide member and reciprocatable lengthwise thereof, a pair 80 of latch members carried by the cross head on each side of the guide, in position to hold a bar while it is traveling guided by said guides, one member of each pair of latches being positioned to overlap a bar, 85 the other member of each pair of latches being adapted to underlap a bar, yielding mechanism normally holding all of the latches in said respective positions, means for reciprocating the cross head along the 90 guide, and cam mechanism carried by the guide engaged by the second mentioned set of levers on the cross head in a given position of movement of the cross head, to automatically move said second set of latches 95 out of the way of a bar previously carried between said latches, for the purposes set forth.

14. In mechanism of the class described, a stationary hollow guide member adapted 100 to be entered by a bar for guiding purposes, a cross head moving parallel to the guide member and reciprocatable lengthwise thereof, a pair of latch members carried by the cross head on each side of the 105 guide in position to hold a bar while it is travelling guided by said guide, one member of each pair of latches being positioned to overlap a bar, the other member of each pair of latches being adapted to underlap a 110 bar, yielding mechanism normally holding all of the latches in said respective positions, means for reciprocating the cross head along the guide, and cam mechanism carried by the guide engaged by the second mentioned set of levers on the cross head in a given position of movement of the cross head, to automatically move said second set of latches out of the way of a bar previously carried between said latches, for the purposes set forth. 115

15. In mechanism of the class described, a vertical stationary guide member of channel cross section adapted to have the end of a bar pass by gravity down its interior, a cross 125 head moving parallel to the guide member and reciprocatable lengthwise thereof, a pair of latch members carried by the cross head on each side of the guide, in position to hold a bar while it is traveling guided by said 130

- guide, one member of each pair of latches being positioned to overlap a bar, the other member of each pair of latches being adapted to underlap a bar, yielding mechanism 5 normally holding all of the latches in said respective positions, means for reciprocating the cross head along the guide, and cam mechanism carried by the guide engaged by the second mentioned set of levers on the 10 cross head in a given position of movement of the cross head, to automatically move said second set of latches out of the way of a bar previously carried between said latches, for the purposes set forth.
- 15 16. In mechanism of the class described, a stationary guide member for a bar, a cross head moving parallel to the guide member and reciprocatable lengthwise thereof, a pair of latch members carried by the cross head 20 on each side of the guide in position to hold a bar while it is traveling guided by said guide, one member of each pair of latches being positioned to overlap a bar, the other member of each pair of latches being adapted 25 to underlap a bar, yielding mechanism normally holding all of the latches in said respective positions, means for reciprocating the cross head along the guide, and cam mechanism carried by the guide engaged by 30 the second mentioned set of levers on the cross head in a given position of movement of the cross head, to automatically move said second set of latches out of the way of a bar previously carried between said latches, and latches carried by the guides operative at 35 said last mentioned position to prevent retreat movement of the bar in the guide.
17. In mechanism of the class described, a stationary hollow guide member adapted to 40 be entered by a bar for guiding purposes, a cross head moving parallel to the guide member and reciprocatable lengthwise thereof, a pair of latch members carried by the cross head on each side of the guide, in 45 position to hold a bar while it is traveling, guided by said guide, one member of each pair of latches being positioned to overlap a bar the other member of each pair of latches being adapted to underlap a bar yielding 50 mechanism normally holding all of the latches in said respective positions, means for reciprocating the cross head along the guide, and cam mechanism carried by the guide engaged by the second mentioned set 55 of levers on the cross head in a given position of movement of the cross head, to automatically move said second set of latches out of the way of a bar previously carried between said latches, and latches carried by 60 the guides operative at said last mentioned position to prevent retreat movement of the bar in the guide.
18. In mechanism of the class described, a vertical stationary guide member of channel 65 cross section adapted to have the end of a bar pass by gravity down its interior, a cross head moving parallel to the guide member and reciprocatable lengthwise thereof, a pair of latch members carried by the cross head on each side of the guide in position to hold 70 a bar while it is traveling guided by said guide, one member of each pair of latches being positioned to overlap a bar, the other member of each pair of latches being adapted to underlap a bar, yielding mechanism 75 normally holding all of the latches in said respective positions, means for reciprocating the cross head along the guide, and cam mechanism carried by the guide engaged by the second mentioned set of levers on the cross head in a given position of movement of the cross head to automatically move said second set of latches out of the way of a bar previously carried between said latches, and latches carried by the guides operative at 80 said last mentioned position to prevent retreat movement of the bar in the guide.
19. In mechanism of the class described, a guide open at one end and along its length so that a bar may traverse said opening, a 90 bar adapted for travel along the guide under its control, a temporary support for the bar at a point remote from the open end of the guide, a bar carrier reciprocatable along the guide toward the support, spring actuated 95 bar gripping mechanism on the carrier adapted to engage two opposite sides of the bar means for moving the bar carrier between two positions in one of which it grasps the bar on the temporary support and in 100 the other of which it still grips the bar now under control of the guide, and automatic means operating the bar gripping mechanism at approximately the last mentioned position to disengage it from the bar and 105 permit it to return to the first position without interference by the delivered bar.
20. In mechanism of the class described, a guide open at one end and along its length so that a bar may traverse said opening, a 110 bar adapted for travel along the guide under its control, a temporary support for the bar at a point remote from the open end of the guide, a bar carrier reciprocatable along the guide toward the support, spring actuated 115 bar gripping mechanism on the carrier adapted to engage two opposite sides of the bar, means for moving the bar carrier between two positions in one of which it grasps the bar on the temporary support and in 120 the other of which it still grips the bar now under control of the guide, and automatic means operating the bar gripping mechanism at approximately the last mentioned position to disengage it from the bar and 125 permit it to return to the first position without interference by the delivered bar, and latch mechanism in connection with the guide, adapted to automatically engage the delivered bar operative as the carrier 130

gripping mechanism releases the bar to hold it with reference to the guide.

21. In mechanism of the class described, a channel shaped guide through whose open 5 side the end of a bar is adapted to pass, a pair of latch levers pivoted on the opposite side walls of said channel provided with latch teeth projecting into the path of a bar traveling down the channel, spring means 10 urging said latches inward toward the center

of the channel, and means limiting such movement.

In witness whereof we have hereunto subscribed our names.
